UNITED STATES PATENT OFFICE.

JOSEPH J. SCHORP AND GEORGE SIGLINGER, OF ST. LOUIS, MISSOURI.

DESIGN FOR A PAD.

SPECIFICATION forming part of Design No. 31,455, dated August 22, 1899.

Application filed July 31, 1899. Serial No. 725,697. Term of patent 7 years.

To all whom it may concern:

Be it known that we, JOSEPH J. SCHORP and GEORGE SIGLINGER, of the city of St. Louis, State of Missouri, have invented and produced a new and original Design for a Pad, of which the following is a full, clear, and exact description, reference being had to the accompanying drawings, forming a part hereof.

In the drawings, Figure 1 is a plan view of a pad showing our new design. Fig. 2 is an edge view of the pad seen in Fig. 1.

As shown in the drawings, the leading or material feature of our design consists of a pair of rectangular bodies 1, the outer end corners of which are rounded, and said bodies are joined by the neck portion 2, which is considerably narrower than the bodies 1, and the side edges 3 of said neck are segmentally curved when seen in plan view. A continuous zigzag ornamental border 4 extends across

the ends of the bodies 1 and along one side thereof, there being a short zigzag ornamental border 5 arranged on the opposite side of the neck 2 from the side on which the ornamental border 4 is arranged. To one side of 25 the neck 2 and on top of one of the bodies 1 appears a circular disk 6, from the center of which projects vertically upward a cylindrical body 7, the same being surmounted by a short circular body 8. 30

We claim—

The design for a pad, substantially as herein shown and described.

In testimony whereof we affix our signatures in presence of two witnesses.

JOSEPH J. SCHORP.
GEORGE SIGLINGER.

Witnesses:

EDWARD E. LONGAN,
ALFRED A. EINES.
